US00D915130S

(12) United States Design Patent (10) Patent No.: US D915,130 S
Elmasu et al. (45) Date of Patent:  Apr. 6, 2021

(54) COOKWARE

(71) Applicant: STMM Inc., New York, NY (US)
(72) Inventors: Celia S. Elmasu, San Jose, CA (US);
Faris Elmasu, San Jose, CA (US)
(73) Assignee: STMM INC., New York, NY (US)
() Term: 15 Years

(21) Appl. No.: 29/677,054

(22) Filed: Jan. 16, 2019

(51) LOC (13) Cl. 07-02

(52) U.S. Cl. D7/360

CLAIM

The ornamental design for cookware, as shown and described.

DESCRIPTION

FIG. 1 is a front perspective view of cookware, shown separately from the lid to show aspects of the design that are not visible when combined, showing my new design;
FIG. 2 is a front view thereof;
FIG. 3 is a back view thereof;
FIG. 4 is a right side view thereof;
FIG. 5 is a left side view thereof;
FIG. 6 is a top view thereof;
FIG. 7 is a bottom view thereof; and
FIG. 8 is a front perspective view of the cookware;
FIG. 9 is a front perspective view of the lid of the cookware shown separately to show aspects of the design that are not visible when combined;
FIG. 10 is a front view thereof;
FIG. 11 is a back view thereof;
FIG. 12 is a right side view thereof;
FIG. 13 is a left side view thereof;
FIG. 14 is a top view thereof; and,
FIG. 15 is a bottom view thereof.
